United States Patent Office.

EPHRAIM SHAW, OF TARR FARM, PENNSYLVANIA.

Letters Patent No. 106,218, dated August 9, 1870.

IMPROVEMENT IN MITERING-MACHINE.

The Schedule referred to in these Letters Patent and making part of the same

To all whom it may concern:

Be it known that I, EPHRAIM SHAW, of Tarr Farm, in the county of Venango and State of Pennsylvania, have invented a new and improved Mitering-Machine; and I do hereby declare that the following is a full, clear, and exact description thereof, which will enable others skilled in the art to make and use the same, reference being had to the accompanying drawing forming part of this specification.

Figure 1 represents a side elevation of my improved mitering-box.

Figure 2 is a plan view of the same.

Similar letters of reference indicate corresponding parts.

This invention relates to improvements in mitering-machines, and consists in the arrangement of parts, as hereinafter specified; a miter-machine of extremely simple construction, but perfect in operation is thus produced.

A in the drawing represents the bed or table of my improved mitering-machine.

To its surface is secured a projecting rib or ledge, a, against which the stuff to be mitered is placed.

From the bed A projects also a post, B, which carries at the end of a horizontal projecting arm b a swivel disk, C.

This disk turns on an arbor, c, which has its bearings in the arm b.

The arm b can be made in two parts, as in fig. 2, between which the disk can be clamped by means of a screw, d, or it may be made in one piece, and receive a suitable set-screw or pin for locking the disk in any desired position.

Through the disk C is fitted diametrically a cylindrical rod, D, which constitutes the stem or shank of the saw-guide E.

The rod can turn in the disk, and can be clamped thereto by a set-screw, e.

The guide E is made in form of a slotted plate, or of two wires or open frames, as shown.

It is evident that in the disk the saw-guide can be set at any desired angle, to cut miters at forty-five or other suitable degrees, while on the axis of the disk the guide may also be swung to set the saw at a slant, and thereby vary the pitch of the miter.

Having thus described my invention,

I claim as new and desire to secure by Letters Patent—

The arrangement of the slotted ring-guide E, provided with the shank or rod D, the disk C, turning on an arbor, c, the clamp-arms b b, clamp-screws d e, and post B, as shown and described.

EPHRAIM SHAW.
